UNITED STATES PATENT OFFICE.

JOHN J. HAZLEWOOD, OF PITTSBURGH, PENNSYLVANIA.

TRANSFER MEANS.

1,298,188.

Specification of Letters Patent.

Patented Nov. 22, 1921.

Application filed May 2, 1919. Serial No. 294,222.

To all whom it may concern:

Be it known that I, JOHN J. HAZLEWOOD, a citizen of the United States, residing at

Pittsburgh, in the county of Allegheny and 5 State of Pennsylvania, have invented certain new and useful Improvements in Transfer Means; and I do hereby declare the following to be a full, clear, and exact description of the invention, such as will enable 10 others skilled in the art to which it appertains to make and use the same.

This invention relates to improvements in transfer devices and its primary object is 15 the provision of a simple, durable and efficient device of the kind adapted to receive work from the forward side of a metal rolling machine and elevate it to a point above the rolls of the machine so that it may be received by the operator to be again passed 20 through the rolling machine or through another machine, as desired.

The invention has for a further object the provision of a transferring device of the character stated in which the receiving tables 25 may be readily moved from one horizontal plane to another horizontal plane and the positions of the tables reversed to carry articles thereon with the minimum expenditure of time and energy.

30 The invention has for a further object the provision of a transferring device of the character stated which may be especially adapted for use in rolling mills, warehouses or other establishments and which will require the minimum amount of space and 35 may be readily operated.

With the foregoing and other objects as will appear as the description proceeds, the invention consists in the novel construction, 40 combination and arrangement of co-operating elements as hereinafter more specifically set forth, claimed and shown in the accompanying drawings, forming a part of the present application and in which:

45 Figure 1 is a perspective side view of a transferring device constructed in accordance with my invention, the device being shown with one of its tables in a receiving position and the other of the tables in a delivering position with respect to a pair of rolls of a metal rolling machine.

Fig. 2 is a similar view illustrating the manner in which one table moves from a receiving to a delivering position and the 50 other tables moves from a delivering to a receiving position.

Fig. 3 is a detail transverse section through the main pulling shaft of one of the tables.

Fig. 4 is a fragmentary top plan view of 60 one of the tables showing a portion of the other table in transverse section and at right angles to the first table to better illustrate the relation between these two tables.

Fig. 5 is a detail longitudinal section 65 through one of the tables.

Figs. 6, 7 and 8 are top plan, side and end views, respectively of one of the tripping standards.

In Figs. 1 and 2 I have illustrated the 70 transfer device designated generally by 1 as used in connection with a set of rolls indicated generally by A of known type, these rolls adapted to receive between them articles which are pressed or rolled thereby, 75 these articles being delivered to lower tables of the transfer device and being then elevated by this device and delivered onto the upper series of rolls so as to be returned to the inlet or feed end of the set of rolls in 80 the known manner. The transferring device may be equally well used in connection with a plurality of elevators such as used in connection with warehouses and similar establishments for receiving articles from one 85 elevator and transferring these articles to another elevator.

The transfer device is provided with a supporting carriage 2 of substantial rectangular outline and channel beam construction which is reciprocally mounted upon a track 3 for movement toward and away from the set of rolls A. Track 3 is supported by a suitable foundation or floor 4 through which extends an elongated slot 5 positioned 90 centrally of the track, this slot accommodating a lever 6 which is rockably mounted at its lower end on a shaft 7 supported by suitable bearing blocks 8 mounted beneath the floor. The upper end of this lever is connected by a link 9 to a bracket 10 secured upon the rear end bar of the carriage 2. The lever is connected intermediate its ends by a link 11 to a disk 12, eccentrically thereof, this disk being secured upon a shaft 13 100 rotatably supported by a bearing standard 105 positioned beneath the floor 4, this shaft being rotated in any suitable manner. By rotating shaft 13 reciprocation is imparted to carriage 2 so as to move the same toward 110 and away from the series of rolls A. Carriage 2 is provided at its diagonally oppo-

site corners with upwardly extending spaced bearing standards 16 provided at their upper ends with bearing sleeves 17 through each of which is rotatably mounted a stub 5 shaft 18. A connecting link 19 is secured on the inner end of this shaft and is pivotally secured at its opposite ends to upper and lower substantially U-shaped or rectangular frames 20 of suitable construction, these 10 frames 20 being open at their forward or inner ends. An operating arm 21 corresponding substantially in length to link 19 is secured upon the outer end of shaft 18, this arm being provided at each end with a 15 guide and trip roller 22. These arms are adapted to be actuated by suitable guide and tripping means so as to move the shaft 18 through a half rotation for each complete reciprocation of carriage 2 thus reversing the relative positions of frames 20, these frames being moved through circular paths of travel about a common axial plane, the stub shafts 18 being positioned in the same horizontal plane.

25 Tripping and guide standards 23 are mounted at opposite sides of track 3 and are so placed as to be at the diagonally opposite corners of carriage 2 when the carriage is in its inner or receiving and delivering position 30 as illustrated in Fig. 1. Each of the standards 23 is provided with an inclined upper portion 24 contiguous to a horizontal portion 25 at its lower end and a vertical stop element 26 at its upper end. On its inner face 35 the standard is provided with two spaced arcuate flanges 27 which form an arcuate guideway 28 adapted to receive the roller 22 at the lower end of arm 21, the lower flange 27 being provided with an opening or cutout 40 at its lower end which is normally closed by a dog 29 secured on the inner end of a stub shaft 30 rockably mounted in the standard, this stub shaft being provided at its outer end with an arm 31 secured thereon 45 upon which is mounted a counterweight 32 for normally holding the dog in raised position. The upper end portion of the upper flange 27 is similarly cut away and is normally closed by a dog 33 which is held in 50 operative position by gravity, outward movement of this dog beyond the vertical being prevented by a stop element or lug 34 formed upon the standard. This upper dog also serves to close a cutout or opening 55 formed in the lower portion of the inclined member 24, as more clearly shown in Fig. 7.

60 The ends of the inner or forward connecting link 19 are secured to shafts 35 which extend transversely of the forward ends of frames 20 and are rockable therein. The ends of the outer link 19 are secured to shafts 36 which are rockable in the outer ends of the frames 20, the frames being thus connected and supported by the links and the 65 parts associated therewith so as to be mov-

able through circular paths of movement, the links 19 being of slightly greater length than the length of the frames 20 so as to readily permit this movement. By rotating the stub shafts 18, the relative positions of the frames 20 may be thus readily alternately reversed by a continuous operation.

70 A tubular member 37 (Fig. 3) such as a section of pipe, is loosely mounted upon shaft 35, this member being provided with 75 diametrically opposite pairs of ears 38 between which are secured the inner end portions of receiving bars 39, these bars being disposed in parallel spaced relation and extending longitudinally of frame 20 so as to 80 form, together with shaft 36 and the parts associated therewith, a receiving and supporting table which is well adapted to receive articles discharged from between the rolls of the series A. Bar 39 is secured between the ears 38 by a suitable securing bolt 40, this bolt also providing a pivot for a weight member 41 which is adapted to overlie the shaft 35 as in Fig. 3, one of these weight members being provided at each side 85 of the shaft so that the lower member normally hangs in substantial vertical position and tends to rock the tubular member 37 about shaft 35 so as to move bars 39 into horizontal position in a manner to be described.

90 Shaft 35 is provided adjacent the inner face of each side bar of frame 20 with a cam 42 secured thereon which is adapted to engage a roller 43 mounted in the inner end of the trip rod 44 which is slideable through supporting straps 45 secured to the side bar of the frame. The outer end portion of this bar is flattened and is bent downwardly and outwardly to provide an element 46 which is 95 secured to an angle bar 47 extending transversely of the outer end of frame 20 and slideable upon a roller sleeve 48 loosely mounted upon a rod 49 carried by brackets 50 secured to the inner face of end bar 20^a of frame 20 100 and projecting downwardly through slots 51 provided through the bar 47. The brackets 50 support, at their upper ends, a rod 52 upon which is rockably mounted a locking plate 53 the inner portion 53^a of 105 which is inclined downwardly and inwardly and is engaged by a wire spring 54 mounted about rod 52, this spring serving to normally hold the plate in raised position with its outer edge portion in engagement with the upper edge of end bar 20^a of the frame. The rod 44 is normally held in retracted position by an expansion coil spring 55 mounted about the same and confined between the outer strap 45 and a collar 56 110 secured on the rod. In this position roller 43 is engaged by cam 42 so as to force the rod 44 outwardly, when shaft 35 is rotated. Each of the locking plates 53 is provided with a slot 57 to accommodate the weight 115

members 41 so as to prevent tilting of the locking plate, and consequent release of the loaded forward table, by being engaged by the weight member.

- 5 With the transferring device in the position illustrated in Fig. 1, an article which has been passed between the rolls will be delivered upon the lower receiving member. Upon rotation of shaft 13, carriage 2 is 10 moved outwardly so as to rotate arms 21 in a clockwise direction into substantial horizontal position, as in Fig. 2. This serves to move the lower table in Fig. 1 upwardly and forwardly in advance of the upper table 15 of Fig. 1, this upper table being moved downwardly and rearwardly. With the two tables in this position, the weight member 41 of the upper table illustrated in Fig. 1 will be engaged by the rearward end bar 20^a 20 of frame 20 of the forward table in Fig. 2 so as to be raised into substantial vertical position thereby, the weight member 41 which is pivoted at the upper side of shaft 35 in Fig. 2 serving, during continued movement of these tables, to rock the bars 39 of 25 the upper table illustrated in Fig. 1, which are shown in vertical position in Fig. 2, into horizontal position. Upon the carriage 2 being moved inwardly so as to be again in 30 the position illustrated in Fig. 1, the rollers 22 at the inner ends of arms 19 will be forced up the inclined elements 24 of the standards 23, so as to be turned into vertical position thereby, these arms being thus moved 35 through one-half of a complete rotation for each complete reciprocation of the carriage. The table which occupies the lower position in Fig. 1 is thus raised so as to occupy the upper position, the article which has been 40 received from between the rollers being thus elevated so as to be delivered upon the upper surface of the top series of rolls and fed along the same to the inlet or feed end thereof. In this manner, any number of articles 45 may be readily received and transferred from one level to another for the purpose specified. Upon the carriage 2 being again moved outwardly away from the series of rolls A, and as the two frames 20 of the tables approach a common horizontal plane, the cams 42 of shaft 35 engage the rollers 43 so as to force the angle bar or plate 47 outwardly, thus releasing the outer ends of the bars 39 so as to permit the table to be rocked, 50 first into a substantial vertical position as in Fig. 2, this table being then rocked into substantial horizontal position by means of the weight 41 during continued relative movement of the two tables. As the table is 55 moved into horizontal position, the outer ends of the bars 39 thereof, which are beveled for this purpose, engage the beveled portion 53^a of the locking plate 53 so as to rock this plate about rod 52, the bars 39 then engaging 60 angle bar 47 which has been returned to op-

erative position by the spring 55 and parts associated therewith, after which the plate 53 is rocked outwardly by the action of spring 54 so as to engage over the beveled ends of bars 39, the table being thus effectually secured in horizontal position, as in Fig. 1. In this manner, the two tables may have their relative positions alternately reversed, and this operation is continuous so that a great number of articles may be transferred 70 from one elevator or conveyer to another within a relatively short time. By referring to Figs. 4 and 5 of the drawings in connection with Figs. 1 and 2, it will be understood that the plate 53 has its main portion 75 extended at a right angle to the frame end bar 20^a while its beveled portion 53^a is spaced above the shaft 36 and this portion must be forced toward the shaft 36 by the beveled ends of the bar 39 as they pass the plate 53 80 for engagement on the bar 47, when the plate 53 will be immediately returned to normal position by means of the wire spring 54, over the beveled ends of the bar 39 and prevent these ends from again moving upwardly. Also this operation of the two tables is accomplished by the reciprocation of the carriage 2, all unnecessary parts being 85 eliminated and a comparatively simple and positive operation obtained.

90 While I have illustrated and described herein the preferred form of my invention, it will be appreciated that in practice certain modifications in details of construction and arrangement of parts may be found desirable, and I intend to include all such variations, as fall within the scope of the appended claims, in this application in which a preferred form only of my invention is disclosed.

105 What I claim is:

1. In transferring means, the combination with means adapted to deliver articles in one plane and receive articles in another plane, of a horizontally movable carriage, a pair of table frames mounted on said carriage for movement around one another during horizontal movement of said carriage, means to operate said carriage, and means to cause operation of said table frames and 110 cause said table frames to change positions.

2. In transferring means, the combination with means adapted to deliver articles in one plane and receive articles in another plane, of a movable carriage, a pair of table frames normally in horizontal superposed position and mounted on said carriage, said table frames being adapted to change positions and move around one another, and means to operate said table frames during 115 120 125 operation of said carriage.

3. In transferring means, the combination with means adapted to deliver articles in one plane and receive articles in another plane, of a carriage, a pair of superposed 130

table frames, mounting means for said table frames carried by said carriage, and means to operate said table frame mounting means to cause said table frames to move around one another and change positions.

4. In transferring means, the combination with means adapted to deliver articles in one plane and receive articles in another plane, of two article receiving tables mounted in superposed spaced relation and normally positioned substantially in the delivering and receiving planes of said means, said tables being mounted for movement through substantial circular paths so as to have their relative positions reversed, and means for moving the article receiving tables toward and away from said delivering and receiving means and for simultaneously operating said tables so as to alternately reverse the relative positions thereof.

5. In transferring means, the combination with means adapted to deliver articles in one plane and receive articles in another plane, of two article receiving tables mounted in superposed spaced relation and normally positioned substantially in the delivering and receiving planes of said means, said tables being mounted for movement through substantial circular paths so as to have their relative positions reversed, and continuously operating means for moving the article receiving tables toward and away from said delivering and receiving means and for simultaneously operating said tables so as to alternately reverse the relative positions thereof.

6. In transferring means, a reciprocable carriage, receiving tables carried thereby and mounted in superposed spaced relation, and means for reciprocating said carriage and for reversing the relative positions of said tables at each complete reciprocation of the carriage.

7. In transferring means, a reciprocable carriage, receiving tables mounted thereon in superposed spaced relation, rockable members for supporting said receiving tables and connected thereto so as to move the receiving tables about each other and reverse their relative positions when rocked through a half rotation, means for reciprocating said carriage, and means for actuating said rockable supporting members so as to move the same through one-half of a

complete rotation upon each complete reciprocation of the carriage.

8. In transferring means, a reciprocable carriage, two table frames mounted on said carriage in superposed spaced relation, receiving members mounted in said frames and rockable about horizontal axes, the receiving members projecting beyond the inner ends of the table frames, means for locking said receiving members in horizontal position, means for releasing the receiving members at predetermined times so as to permit movement of the frames about each other, and means for reciprocating the carriage and for causing movement of the frames carrying the receiving members about each other so as to have their relative positions reversed after each complete reciprocation of the carriage.

9. In transferring means, a reciprocable carriage, table frames mounted on said carriage in superposed spaced relation, means for supporting said table frames so as to be movable about each other so as to have their relative positions reversed, receiving members rockably mounted in said table frames and projecting beyond the inner ends thereof, means for normally locking said receiving members in horizontal position and for releasing said members so as to permit the frames to pass each other, means for rocking said receiving members into horizontal position after release of the same from said locking means and during continued movement of the table frames relative to each other, and means for reciprocating said carriage and for operating the table frames so as to reverse the relative positions of the receiving members alternately for each complete reciprocation of the carriage.

10. In transferring means, a carriage, a pair of table frames mounted in superposed relation on said carriage, means for moving said carriage in a horizontal plane, and means for operating said table frames during movement of said carriage to cause said table frames to move through substantial circular paths and change positions.

In testimony whereof I affix my signature in presence of two witnesses.

JOHN J. HAZLEWOOD.

Witnesses:
